HENRY ACKERMAN, OF PITTSBURG, PENNSYLVANIA.

Letters Patent No. 80,892, dated August 11, 1868.

IMPROVEMENT IN CORN-PLANTERS.

The Schedule referred to in these Letters Patent and making part of the same.

TO ALL WHOM IT MAY CONCERN:

Be it known that I, HENRY ACKERMAN, of Pittsburg, in the county of Allegheny, and State of Pennsylvania, have invented a new and useful Improvement in Corn-Planters; and I do hereby declare the following to be a full, clear, and exact description of the nature thereof, sufficient to enable others skilled in the art to which my invention appertains to fully understand and use the same, reference being had to the accompanying drawings, making part of this specification, and in which—

Figure 1 is a top or plan view of the device illustrating my invention.

Figure 2 is a bottom view of the rear part thereof.

Figure 3 is a side view thereof.

Figure 4 is a central vertical section of the corn-box and rotating spindle.

Figure 5 is an elevation of the marker.

Similar letters of reference indicate corresponding parts in the several figures.

My invention is a new and improved device for planting corn, whereby it may be planted in several rows, and at different distances. Means are also afforded to allow the carriage to pass over irregular surfaces, and to raise and lower the drills when occasion requires it.

The rotating spindle is provided with peculiar-shaped cells, and brushes are arranged therewith, so that the desired number of kernels are dropped at the proper time.

A marker is also provided, which may be quickly applied to and removed from the rotating spindle, as will be hereinafter more fully described.

In the drawings—

A A' represent the frame of my corn-planter, which is supported at one end by a single wheel or roller, B, and at the other end by two wheels, c c, their axle C being pivoted to a cross-beam, D, above it. This cross-beam D is firmly attached to the main frame A by two metal plates, d d, and another plate, d', is fastened to frame A, and passes into a slot in the centre of the axle-tree C, to keep the bolt C' in the proper position. A bolt, a, is intended for the attachment of the tongue, and b b is an ordinary fifth-wheel. The cross-beams A' A' of frame A support a plate, E, to which are fastened a number of seed-boxes, F, and the driver's seat G, partly seen in fig. 1. Slots are formed in this plate, to allow the seed to drop through them. A cylindrical revolving distributor or spindle, H, passes through the lower end of seed-boxes, and is provided with cups or cells h, adapted to receive the seed intended to be planted, at certain distances in the field. A block, I, is fastened within each seed-box F, and serves as means for fastening brushes i thereto. These brushes i bear on the surface of the spindle or distributor H over the cells h. When the spindle revolves and the cells are filled, the brushes allow only so many grains to pass around in the cell as to be even with the surface of the spindle H. The surface at the rear part of the cell is cut down, as seen at h' in fig. 4. This overcomes a difficulty that is experienced in all similar distributors without the reduced surface h'. The brushes i readily sweep the seeds over the forward edge h², but the rear edge, h', being the same height as the brush, any seed caught at its centre by said edge h' will catch the brush, also, and in its revolving motion bend it over and carry it between the distributor and its enclosure, while other seeds above and around will occasionally slip in the so-formed aperture and obstruct and impede the operation of the distributor H. It is evident that this cannot happen with the arrangement shown in fig. 4, for any kernels caught by the edge h', and carried against the brush i, will be turned by it over the said edge and pushed easily ahead on the reduced surface, providing that the edge h' and brush i do not open enough to allow a kernel to pass between them. The seed-boxes F are fastened to the plate E by means of metal braces f or other means. K is an ordinary clutch, sliding on H, which is provided with a feather, to cause said clutch to turn with H, but have free lateral motion. It is operated by a shifting-lever, k, and receives its motion from a loose pulley, L, provided with shoulders to match similar shoulders on said clutch. The pulley L receives its motion from a series of pulleys or cones M, fastened to the axle of wheel B, through the medium of a belt or chain, or equivalent. ll are

pedestal-bearings for the distributer H. m are levers by which the cultivators m' m' are operated, and to which they are fastened, the middle one having its bearings in the frame A' A', and the outer ones in swinging frames N N, which are attached to frame A by hinges n n, so that they may swing in a vertical direction. To the end of each of these swinging frames is a wheel, O, which acts as a support, and also, like wheel B, as a roller to press the ground down and over the seed when sown.

Fig. 5 represents a T-shaped indicator, shank f² of which can be inserted into an opening, f¹, in the distributer H. The points f³ enter the ground alternately, when the machine is in motion, and leave marks by which the operator can tell at what distance the seed-cups h discharge their contents. The pulleys or cones M give him opportunity to change the speed of the distributer when desired. If he sets the machine in motion again, and finds the distances marked by the indicator to be proper, he removes the indicator and continues planting without it.

The framework of my machine, resting on three wheels G e e, (according to the principle that three points determine the situation of a plane,) presents several advantages, since the condition of the ground cannot interfere with the equal distribution of weight on the fifth-wheel arrangement, while on four-wheel vehicles the case is exactly the reverse. The hinged frames N, resting on wheels O, are able to follow the undulations of the ground and carry their respective cultivators with them, always at the proper height, without ever changing the depth of the furrow.

This simplifies the driver's business to a great extent, as he need only raise the cultivator out of the way of stones and stumps. The wheel B, supporting a greater weight than wheels O O, might be prevented from making too deep a depression in the ground by making said wheel broader than the wheels or rollers O.

Having thus described my invention, what I claim as new, and desire to secure by Letters Patent, is—

1. Supporting the rear of the planter by a single wheel, B, mounted on a rigid frame, in combination with the side wheels O, mounted on hinged frames, substantially as and for the purpose described.
2. The cultivators m', secured at their upper ends to the angular levers m, substantially as and for the purpose described.
3. The removable T-shaped marker, substantially as and for the purpose described.

To the above I have signed my name, this 12th day of May, A. D. 1868.

HENRY ACKERMAN.
